L. L. SCOTT

REFRIGERATING SYSTEM

Filed June 8, 1922

FIG. 1.

FIG. 2.

Lewis L. Scott
INVENTOR
BY

ATTORNEY

UNITED STATES PATENT OFFICE.

LEWIS L. SCOTT, OF ST. LOUIS, MISSOURI.

REFRIGERATING SYSTEM.

Application filed June 8, 1922. Serial No. 566,802.

To all whom it may concern:

Be it known that I, LEWIS L. SCOTT, a citizen of the United States, residing in the city of St. Louis and State of Missouri, have 5 invented a new and useful Improvement in Refrigerating Systems, of which the following is a specification.

The invention relates to mechanical domestic refrigerating units which are usually 10 operated by an electric motor. The object of the invention is to provide a condenser which is arranged to be either water or air cooled or both and which can be located at some point away from the balance of the 15 apparatus and to provide a valve for controlling the water for cooling the condenser, which valve is opened and closed according to the temperature of the condenser coils and to so locate the valve so that any leak 20 past the stem of the valve will be caught in the water container which carries the water for cooling the condenser coils.

In the accompanying drawings Figure 1 25 is a diagram of the entire refrigerating system. Figure 2 is a top view of a portion of the condenser coils, showing a section of the water control valve and the thermostat which operates the valve.

Referring now to the drawings, the 30 numeral 1 indicates an air cooled compressor, 2 is a motor for driving the compressor, 3 is the discharge pipe running to the top coil of the condenser 4, which condenser is formed of tubing in an elongated O shape. 35 The coils are separated by the spacers 5. The coils are all in series and the bottom coil connects to the expansion valve 6, which valve 6 connects to the expansion coil 7 and from coil 7 to the intake piping 8 of the compressor. A rectangular pan 9 surrounds 40 the lower coils of the condenser 4 and is adapted to receive water from the supply pipe 10 through valve 11 and pipe 12. The numeral 13 indicates an overflow pipe which 45 may be run to any convenient point. 14 is a piece of thermostatic metal which is attached to the upper coil of the condenser 4. One end of the thermostatic metal is connected to the stem 15 of the water control

valve, which valve is adapted to be opened 50 or closed according to the temperature of the condenser. It will be noted that the water valve is so located that any leak that might take place around the stem of said valve will be caught in the pan 9. The condenser 4 is so designed that it will condense 55 the refrigerant, which is usually sulphur-dioxide, either by air cooling alone or by air and water cooling. Where water is used to assist in condensing, it is not necessary to 60 provide a safety device to shut down the motor in case the water supply should fail, because the condenser is so designed that the air cooling will prevent excessive pressure 65 in the refrigerating line. I have found that where air cooling is used alone, it is not effective in very warm weather and very undesirable in apartments where there is no 70 basement to locate the condenser and other parts. Air cooling is very desirable for the 75 cooler weather because of the saving in water and because the freezing trouble with water is eliminated. By arranging the condenser for either air or water cooling and by separating the condenser from the balance 80 of the apparatus I gain advantages that have not heretofore been enjoyed.

What I claim is:

In a refrigerating system, a condenser for condensing the refrigerant having coils arranged one above the other, a box-like pan arranged around the lower coils of the condenser, a valve located above said pan through which water is supplied to the pan for cooling coils located in the pan, a valve member having a stem slidably mounted in said valve for controlling its operation, a thermostatic bar rigidly secured at one end to a coil of said condenser and having a movable end secured to the end of said stem, whereby, according to the temperature 85 around the condenser, said stem will be moved by the thermostatic bar to control the flow of water through said valve to said box-like pan. 90

Signed at St. Louis this 5th day of June, 95 1922.

LEWIS L. SCOTT.
